REGULATING PUMP

Didier Lombard, Pont-Saint-Pierre, Eure, France,
assignor to Societe Dosapro Milton Roy

Filed Aug. 8, 1973, Ser. No. 386,506

Claims priority, application France Feb. 15, 1973

Term of patent 14 years

Int. Cl. D15—02

U.S. Cl. D65—1 R

FIG. 2

FIG. 1

FIG. 1 is a front and side perspective view of a regulating pump showing my new design.

FIG. 2 is a side perspective view thereof.

The undisclosed side is a mirror image of the side shown and the rear is substantially flat and unornamented.

I claim:

The ornamental design for a regulating pump, as shown and described.
